OUTDOOR LIGHTING FIXTURE

Harold L. Kinnear, Chagrin Falls, and Russell C. Ankrum,
Cleveland, Ohio, assignors to The Standard Oil Company,
Cleveland, Ohio, a corporation of Ohio

Filed July 5, 1962, Ser. No. 70,830

Term of patent 14 years

(Cl. D48—31)

FIG. 1 is a front elevational view of an outdoor lighting fixture embodying our new design;

FIG. 2 is a top plan view thereof;

FIG. 3 is a side elevational view thereof, the opposite side being substantially the same; and

FIG. 4 is a bottom plan view thereof.

The opposite side and rear views of our ornamental design are identical to the side and front views, respectively, illustrated.

We claim:

The ornamental design for an outdoor lighting fixture, as shown and described.
